UNITED STATES PATENT OFFICE

151,727

DESIGN FOR A MITER BOX

Harry J. Ziemann, Wauwatosa, Wis.

Application July 18, 1947, Serial No. 140,353

Term of patent 14 years

(Cl. D93—4)

To all whom it may concern:

Be it known that I, Harry J. Ziemann, a citizen of the United States, residing at Wauwatosa, in the county of Milwaukee and State of Wisconsin, have invented a new, original, and ornamental Design for a Miter Box, of which the following is a specification, reference being had to the accompanying drawing, forming part thereof.

Fig. 1 is a view in perspective of a miter box, showing my new design.

Fig. 2 is a view in rear perspective of the miter box shown in Fig. 1.

Fig. 3 is a plan view of the miter box shown in Fig. 1.

I claim:

The ornamental design for a miter box, as shown.

HARRY J. ZIEMANN.
